AMPLITUDE LIMITER

Jacob van Slooten, Eindhoven, Netherlands, assignor, by mesne assignments, to Hartford National Bank and Trust Company, Hartford, Conn., as trustee

Application April 19, 1946, Serial No. 663,428
In the Netherlands November 6, 1941

Section 1, Public Law 690, August 8, 1946
Patent expires November 6, 1961

6 Claims. (Cl. 179—171)

1

For limiting the amplitude of electrical oscillations use is frequently made of so-called limiters. In a very general form these limiters are mainly constituted by one or two high-vacuum discharge tubes which are operated by the oscillations to be limited, in such manner that, in accordance with the amplitude of these oscillations, they draw, to a higher or lower extent grid currents. Consequently they displace their own operating points more or less in the direction of or beyond the cut-off point. If the operating point is located exactly at the cut-off point, then the positive wave halves of the incoming oscillations are still fully active. However, beyond this cut-off point, the flow of anode current is, to an increasing extent, caused only by the positive voltage peaks becoming gradually narrower. Thus, the phenomenon occurs that, with a gradual increase of input voltage, the output voltage of the tube at first slowly increases, then remains substantially constant for a short time, but subsequently starts to decrease. This does not satisfy the principle requirement of a good limiter, which is that the output voltage must remain substantially constant above a definite value of the input voltage. The drawback is caused by the fact that the amplitude of the active incoming positive voltage peaks is maintained approximately constant, but the angle 2ϕ , as a part of the period 2π during which these peaks are present, becomes smaller with an increased in input voltage, due to these peaks becoming gradually narrower, as above described. The mean anode current thus also decreases, as well as the amount of energy per cycle in the output circuit.

The present invention has for its object a simple means whereby this drawback is obviated. It consists in so choosing the operating conditions of the tube that, within the control region of the input voltages, the decrease of output voltage which with an increase in input voltage would be due to the mean grid voltage becoming more strongly negative, is approximately compensated.

These conditions may be obtained in different manners, for instance by a correct choice of the grid leak resistance which determines the instantaneous value of the grid bias, and by including a resistance in the cathode lead having such a value that, with an increase in signal intensity, the mean anode current may be maintained substantially constant due to lower voltage drop in this resistance and higher voltage drop in the grid leakage resistance.

If the discharge tube used is a pentode or other tube in which very high internal resistances may

be obtained, it is advantageous to choose the mean anode voltage to be applied of such value that the rise of this voltage in itself entails also an increase of the mean anode current.

5 In order to cause the anode voltage to increase with an increase in negative grid-bias, it is of course necessary that the external anode circuit should have a certain resistance. In the case of a screen-grid tube it is possible to connect in 10 parallel thereto, or instead thereof, a resistance in the conductor leading to the screen grid so that, with an increase in signal intensity and consequently an increase in negative bias of the control grid, the screen grid potential will increase 15 and contribute to maintaining constancy of the mean anode current, which in itself would decrease due to the control-grid voltage becoming more negative.

As a matter of fact, the invention is based on 20 the recognition of the fact that limiter circuits drawing grid current exhibit a good limiter action only if care is taken to insure that the mean anode current remains substantially constant within the control region, since in these circuits this will also 25 be the case with the alternating current component (at least with signals not too weak).

According to the invention, in the case of a 30 pentode use may also advantageously be made of an adjustable potential on the third or suppressor grid, in order to adjust the value to which the output voltage is limited.

In order that the invention may be more clearly understood and readily carried into effect, it will 35 be described more fully by reference to the accompanying drawing forming a part of the specification and in which:

Fig. 1 shows a graph of the output voltage as a 40 function of the input voltage at different values of the grid resistance for a grid-leak limiter circuit, such as shown in Fig. 2,

Figs. 2 and 3 are two different embodiments of 45 the invention, and

Fig. 4 shows a few dynamic characteristic curves of the circuit shown in Fig. 3.

The curves I to VI shown in Fig. 1 give the 50 variation of the output voltage V_o of a grid-current limiter circuit as shown in Fig. 2 as a function of the input voltage V_i and this at six different values of the grid-leakage resistance. This amounted to 4600 ohms for curve I and rose to infinity for curve VI. For low values of V_i the rising curves coincide but then diverge. Curve I continues to rise, curve II at first remains substantially plane and then rises further, whereas curves III—VI initially exhibit a drop which con-

tinues with VI and changes later into a rise with III—V. Curves II and III only exhibit a variation which might to some extent be used for a limiter action. The associated values of the leakage resistance, viz. 22,000 and 58,000 ohms respectively are, however, so small that the circuit cannot be used in a conjunction with a tuning circuit of good quality, since such a circuit would be far too strongly damped. With the higher values which may be used in this respect for the leakage resistance, for example 500,000 to 600,000 ohms (curve V) the output voltage declines too much as a result of the reasons above-described.

In the circuits of Figs. 2 and 3 which are applicable to frequency modulation receivers and which will now be described care has been taken in different manners to insure that a satisfactory limiter action is obtained in spite of a sufficiently high leakage resistance.

In the circuit shown in Fig. 2, a limiter tube 1 of any desired type may be used. Tube 1 may, for instance, by a type EF50, connected as a triode by interconnecting the screen grid and anode electrodes. In general, any high conductance triode or triode-connected tube will be satisfactory. The desired effect is obtained by connecting a high resistance 3 bridged by a condenser 2 in the supply conductor leading to the cathode of the tube. The order of magnitude of this resistance is 10,000 ohms, whereas that of the leakage resistance 4 may amount to 500,000 ohms or higher. By means of a source of supply 5, the bias for the grid must in this case be made positive relatively to the earthed end of the resistance 3, since the total voltage drop in this resistance may easily amount to 50 volts and higher.

In this case the control voltage for automatic volume control may be derived from the grid end of the resistance 4 in the usual manner via a resistance 6.

Due to the presence of the high cathode resistance 3, the mean anode current and hence the output voltage may be maintained sufficiently constant and the tube operates very satisfactorily as a limiter.

In the construction shown in Fig. 3 use is made of a pentode tube 7 having a grid leakage resistance 8, a screen-grid resistance 9 and an anode series-resistance 10. The voltage on the third grid is made variable. In the circuit of Fig. 3 a tube type EF50 has given satisfactory results. Another example of a suitable tube is a type EF42. The value of the resistance 10 is now so chosen that the mean anode voltage is so low that variations in this voltage still bring about considerable variations in the mean anode current and vice versa. Consequently, with an increase in signal intensity, in which case the negative bias on the control grid rises, the anode voltage will increase and counteract the effect of the control grid upon the mean anode current. The latter may consequently be maintained substantially constant and the same applies to the output voltage. Moreover, a resistance 9 is provided in the screen-grid conductor so that not only the mean anode potential but also the screen-grid voltage will increase with the intensity of the signal and contribute to maintaining constancy of the mean anode current.

Fig. 4 illustrates graphically the limiter action of this circuit on a double logarithmic scale. In this case the resistance 8 had a value of 600,000 ohms and the resistances 9 and 10 values of

100,000 and 64,000 ohms respectively. The voltage of the anode battery amounted to 150 volts. Curve A represents the variation of the output voltage V_o as a function of the input voltage V_i with a bias on the third grid of +4 volts, whereas curve B represents the same variation with -6 volts. Consequently, variation of this bias apparently only results in a displacement of the horizontal portion of the curve parallel to itself so that, with the aid of this variation, the adjustment of the value to which limitation of the output voltage is desired is possible within definite limits.

I claim:

1. A circuit arrangement for limiting the amplitude of a radio frequency signal voltage, comprising an electron discharge tube having an input circuit including a cathode electrode and a control electrode and an anode electrode, and an output circuit including said cathode, means to apply operating potentials to said tube, means to apply said signal voltage to the input circuit, means to bias the control electrode of said tube below the cut-off value, said means comprising a grid-leak resistor interposed between the control electrode and cathode electrode of said tube and having a value at which successive increases of the signal voltage above a given value normally produce a decrease in the cathode-anode current, a resistance element in said output circuit having a value at which the voltage drop across the said resistance element establishes an operating point of said tube at which the said decrease in the cathode-anode current is substantially neutralized, and means to by-pass said latter resistance element for said signal voltage.

2. A circuit arrangement for limiting the amplitude of a radio frequency signal voltage, comprising an electron discharge tube having an input circuit including a cathode electrode and a control electrode, and an output circuit including said cathode and an anode electrode, means to apply operating potentials to said tube, means to apply said signal voltage to said input circuit, means to bias the control electrode of said tube below the cut-off value, said means comprising a grid-leak resistor interposed between the control electrode and cathode electrode of said tube and having a value at which successive increases of the signal voltage above a given value normally produce a decrease in the cathode-anode current, a cathode resistor coupled to the cathode of said tube and having a value at which the voltage drop across the said cathode resistor establishes an operating point of said tube at which the said decrease in the cathode-anode current is substantially neutralized, and means to by-pass said cathode resistor for said signal voltage.

3. A circuit arrangement for limiting the amplitude of a radio frequency signal voltage, comprising an electron discharge tube having an input circuit including a cathode and a control grid and an output circuit including said cathode, a screen electrode and an anode electrode, means to apply operating potentials to said tube, means to apply said signal voltage to said input circuit, means to bias the control grid of said tube below the cut-off value, said means comprising a grid-leak resistor interposed between the control grid and cathode of said tube and having a value at which successive increases of the signal voltage above a given value normally produce a decrease in the cathode-anode current, a resistance element in said output circuit interposed between

said operating potential application means and one of said electrodes and having a value at which the voltage drop across the said resistance element establishes an operating point of said tube at which the said decrease in the cathode-anode current is substantially neutralized, and means to by-pass said latter resistance element for said signal voltage.

4. A circuit arrangement for limiting the amplitude of a radio frequency signal voltage, comprising an electron discharge tube having an input circuit including a cathode and a control grid and an output circuit including said cathode, a screen grid and an anode, means to apply operating potentials to said tube, means to apply said signal voltage to said input circuit, means to bias the control grid of said tube below the cut-off value, said means comprising a grid-leak resistor interposed between the control grid and cathode of said tube and having a value at which successive increases of the signal voltage above a given value normally produce a decrease in the cathode-anode current, a resistance element in said output circuit interposed between said anode and the anode potential application means and having a value at which the voltage drop across the said resistance element establishes an operating point of said tube at which the said decrease in the cathode-anode current is substantially neutralized, and means to by-pass said latter resistance element for said signal voltage.

5. A circuit arrangement for limiting the amplitude of a radio frequency signal voltage, comprising an electron discharge tube having an input circuit including a cathode and a control grid and an output circuit including said cathode, a screen grid and an anode, means to apply operating potentials to said tube, means to apply said signal voltage to said input circuit, means to bias the control grid of said tube below the cut-off value, said means comprising a grid-leak resistor interposed between the control grid and cathode of said tube and having a value at which successive increases of the signal voltage above a given value normally produce a decrease in the cathode-anode current, a resistance element in said output circuit interposed between said operating potential application means and said screen-grid and having a value at which the voltage drop across the said resistance element establishes an operating point of said tube at

which the said decrease in the cathode-anode current is substantially neutralized, and means to by-pass said latter resistance element for said signal voltage.

- 5 6. A circuit arrangement for limiting the amplitude of a radio frequency signal voltage, comprising an electron discharge tube having an input circuit including a cathode and a control grid and an output circuit including said cathode, a screen grid and an anode, means to apply operating potentials to said tube, means to apply said signal voltage to said input circuit, means to bias the control electrode of said tube below the cut-off value, said means comprising a grid-leak resistor interposed between the control grid and cathode of said tube and having a value at which successive increases of the signal voltage above a given value normally produce a decrease in the cathode-anode current, an output impedance element coupled to the anode of said tube, a first resistance element in said output circuit interposed between said output impedance element and said potential application means and having a value at which the voltage drop across the said resistance element establishes an operating point of said tube at which the said decrease in the cathode-anode current is substantially neutralized, a second resistance element interposed between said potential application means and said screen-grid and having a value at which successive increases of said signal voltage above said given value successively increases the screen-grid potential to aid in neutralization of said decrease in the cathode-anode current, and means to by-pass said first and second resistance elements for said signal voltage.
